UNITED STATES PATENT OFFICE

1,924,539

SMOKING PIPE

Stanley Brown, Garden City, N. Y.

Application November 2, 1929. Serial No. 404,293

5 Claims. (Cl. 131—12)

The object of my invention is to produce a smoking pipe of simple and inexpensive construction, of great strength at the union of its bowl and stem and with unusual facility for 5 thorough cleaning.

The invention therefore comprises a stem of approximately its maximum size where it is to engage with the bowl and a correspondingly large opening or openings in the bowl to receive 10 such a stem whereby I not only provide a very strong joint between the bowl and stem but I greatly facilitate the cleaning of all parts. The invention also comprises a stem so constructed that it will contribute to form the bottom of the 15 bowl and preferably an oscillable stem which has a lifter or lifters for detaching or loosening contents of the bowl.

In the accompanying drawing which illustrates embodiments of my invention:

20 Fig. 1 is an outside side view of a smoking pipe.
Fig. 2 is an outside view of the bowl alone.

Fig. 3 is a central longitudinal section of a pipe.

25 Fig. 4 is a central longitudinal section of a pipe having a bowl slightly modified in form.

Fig. 5 is a top view of the bowl shown in Fig. 3.

Fig. 6 is a side view of the stem of the pipes shown in Figs. 1, 3 and 4.

30 Fig. 7 is a central longitudinal section of a pipe of modified form.

Fig. 8 is an outside view of the bowl which is included in Fig. 7.

Fig. 9 is a central longitudinal section of a pipe of modified form.

35 Fig. 10 is a transverse section at the line A—A of Fig. 6.

Similar letters of reference designate corresponding parts in all the figures.

Referring first to Figs. 1, 2, 3, 4, 5, 7, 8 and 9; 40 1 designates the pipe bowl. It may be of any desired shape and made of wood or any other material suitable for use as a pipe bowl. It is shown as substantially cylindric externally and of inverted conical form 3 internally. In Fig. 4 it is shown as having a closed bottom 4 but in Fig. 3 it is shown as being open from end to end.

In Fig. 9 the bowl is shown as having a single transverse opening 5 from its exterior to its interior. This opening is a large opening and of approximately the maximum size of the exterior 45 of the stem 2 of the pipe.

In Figs. 3 and 4 the pipe bowl has a transverse opening 6 from its exterior to its interior and this opening is opposite the opening 5 of this 50 bowl.

The stem 2 will preferably be made of non-absorbent material. Bakelite will be very suitable. It is of substantially maximum size at the end which is to communicate with the bowl but preferably it will taper slightly at its end portion 60 which is to be engaged with the bowl and the holes 5 and 6 will be correspondingly tapered to enable the stem to be tightly and securely engaged with the bowl.

In Figs. 1, 3 and 4 the stem is shown to be 65 straight and it engages with the bowl approximately at a right angle to the axis of the bowl but in Fig. 7 the opening 5 of the bowl is oblique to the axis of the bowl and the opening 6 extends through the lower end of the bowl. The stem 70 2 therefore engages obliquely with this bowl. It and the holes 5 and 6 will preferably be tapered as in the other illustrated examples of my invention.

That portion 7 of the stem which is to be 75 within the bowl contributes to form the bottom of the bowl and may advantageously be concaved or recessed on its upper surface.

When the stem is extended into a hole 6 it 80 forms a stopper for the latter.

In all the illustrated examples of my invention that portion 7 which is within the bowl is provided with a lifter or lifters which by oscillating the stem relatively to the bowl will lift 85 more or less of the contents of the bowl.

Referring to Fig. 10; when the portion 7 of the stem within the bowl is concaved the side edges 8 and 9 of the concaved portion will constitute lifters.

In Fig. 5 will be seen the large communication 90 10 from the interior of the bowl to the recess for the stem. The conical hole 3 is shown to extend through the bottom of the bowl at the opening 11. The bottom of the bowl of the pipe 95 is preferably flat as shown so that the pipe will rest upon the bottom when the pipe is set down and the lower side of the stem is as nearly flush with the bottom as convenient, the holes in the side being so located as to hold the stem in such position.

Any cooling or other devices known in the art may be added to my pipe if they will not interfere with the characterizing features of my invention.

It will be seen that I have produced a smoking pipe which is very simple and inexpensive, which has a very strong union between its bowl and stem because of the large size of the stem where it engages with the bowl, and which may be very easily and thoroughly cleaned because of the large 110

opening or openings for the stem and the large communication between the interior of the bowl and the recess for the stem.

What I claim as my invention and desire to secure by Letters Patent is:

1. A smoking pipe comprising a bowl having two transversely aligned openings in the wall thereof and an opening in its bottom, and a stem passing through said transverse openings and forming a closure for said bowl to all said openings, and having a smoke hole communicating with the bowl.

2. A smoking pipe comprising a shankless bowl having two transversely aligned openings in the wall thereof and an opening in its bottom, and a stem passing through said transverse openings and forming a closure for said bowl to all said openings, and having a smoke hole communicating with the bowl, the portion of the stem within the bowl having a substantially solid cross-section with a concave surface forming a bottom for the bowl.

3. A smoking pipe having a bowl with a cavity therein and a stem to be connected to the bowl, the latter having a transversely extending opening in one side close to the bottom of the bowl to receive one end of the stem and hold the stem in position with its lower side nearly flush with the bottom, the upper side of the stem within the bowl having an enlarged recess which serves as the bottom for the cavity in the bowl, the bot-

tom of the bowl also having an opening therethrough which is sealed from the tobacco cavity by the stem when the latter is attached to the bowl.

4. A smoking pipe comprising a bowl and a stem to be connected thereto, the bowl having a transversely extending opening in one side to receive the end of the stem and retain the latter in position with its lower side approximately flush with the bottom of the bowl, said bottom being somewhat flattened on its outside and having an opening therein which is sealed from the tobacco cavity by the inner end of the stem when the latter is attached to the bowl, the stem also having an enlarged recess in its upper side within the bowl serving as the bottom of the cavity and the smoke passage through the stem communicating with said cavity.

5. A smoking pipe having a bowl with a cavity therein and a stem to be connected to the bowl, the latter having a transversely extending opening in one side close to the bottom of the bowl to receive one end of the stem and hold the stem in position with its lower side nearly flush with the bottom, the upper side of the stem within the bowl forming part of the bottom for the cavity in the bowl, the bottom of the bowl also having an opening therethrough which is sealed from the tobacco cavity by the stem when the latter is attached to the bowl.
